UNITED STATES PATENT OFFICE.

PAUL PRIEM, OF HEIDENHEIM-ON-THE-BRENZ, GERMANY, ASSIGNOR TO AMERICAN
VOITH CONTACT COMPANY, INC., OF NEW YORK, N. Y., A CORPORATION OF NEW
YORK.

WOOD GRINDER.

Application filed December 20, 1923. Serial No. 681,815.

To all whom it may concern:

Be it known that I, PAUL PRIEM, a citizen of the Republic of Germany, and residing at Heidenheim-on-the-Brenz, Germany, have invented certain new and useful Improvements in Wood Grinders, of which the following is a specification.

This invention relates to the grinding of wood into pulp used in the manufacture of paper and more particularly to improvements in the feeding device of grinders of the continuously working type. The present application as also my co-pending application, Serial No. 567,778, filed June 12, 1922, relates in particular to the construction of the feeding device which is used in such grinders.

As set forth in my said co-pending application it has been observed, that only the blocks which are in direct engagements with the feed devices—that is to say, only those of the sides of the wood column—are forced, against the grind stone with the desired pressure. According to the previous invention, this difficulty is overcome by increasing the feed pressure on the interior of the charge by increasing the lateral pressure of the feed devices against the sides of the block mass. In this way, the grip of the feeders on the sides of the charge is transmitted to the interior of the mass, and the latter is forced against the grinder with the same pressure as the marginal areas thereof.

A new way of accomplishing this is represented in the accompanying drawing in which is shown a feed device of a special design.

Referring to the figure, I have indicated a pair of chains with links 1, having each the form of a wedge block with its inclined surface toward the stone 4. Near the stone 4, the chains are driven in a well known manner by sprockets 3 fastened each to a shaft 2. The chains are endless and carried by similar sprockets (not shown in the drawing) at the upper portion of the hopper. The feeding device is operated by turning the shafts 2 in the sense of the arrows.

With this design, the above mentioned increasing of the inward pressure is attained by the fact, that, when the chains are moving toward the stone in excess of the rate of consumption of the wood, the wood blocks 5, 6, 7 and 8, 9, 10 f. i. glide into the

respective positions 5¹, 6¹, 7¹, and 8¹, 9¹, 10¹, thereby increasing the pressure in the interior of the wood column. At the same time the internal friction of the charge, is also increased with the result that the wood blocks in the middle of the hopper are pressed against the grinding surface with the same force as the marginal blocks.

Although a certain specific form of apparatus has been described, it is to be clearly understood, that the invention is not limited to these details of construction and that suitable changes may be made without departing from the spirit of the invention.

I claim:

1. A wood grinder of the continuously working type comprising the combination of a grinding element and endless feed chains for positively feeding a charge of wood blocks against the stone, said feed chains consisting of wedge shaped links with their inclined surfaces directed toward the stone.

2. A wood grinder of the continuously working type comprising the combination of a grinding element, endless feed chains for positively feeding a charge of wood blocks against the stone, said feed chains consisting of wedge shaped links with their inclined surfaces directed toward the stone and means for moving the feed chains in excess of the rate of consumption of the wood blocks.

3. In a wood grinder, feed means for advancing a charge of wood blocks toward the grind stone and comprising a wedge member laterally applied to the charge and adapted for sliding engagement therewith, together with means for driving said wedge member toward the stone at a speed in excess of the consumption of the charge by the stone to cause slip between the wedge member and the charge, and a resulting lateral compacting of the charge as it approaches the stone.

4. In a wood grinder, feed means for advancing a charge of wood blocks toward the grind stone, said feed means comprising oppositely faced wedge members applied to opposite sides of the charge and adapted for sliding engagement therewith, and means for driving said members simultaneously toward the stone at a speed in excess of the consumption of the charge by the stone to cause slip between said wedge

members and the charge, and a resulting lateral compacting of the charge as it approaches the stone.

5. The method of feeding a charge in a wood grinder which consists in applying wedge feed means laterally to the charge, and causing slip between said feed means

and the charge to compact the latter as the feed means advances toward the stone.

In testimony that I claim the foregoing 10 as my invention, I have signed my name hereunder.

PAUL PRIEM.
